UNITED STATES PATENT OFFICE

HERMANN BAUER, OF STUTTGART, GERMANY

MACHINE FOR CLASSING BED FEATHERS

Application filed February 15, 1928, Serial No. 254,372, and in Germany February 21, 1927.

My invention relates to machines for classing bed feathers in flowing air and it is an object of my invention to provide a more versatile machine of this kind than has heretofore been designed.

To this end, I provide means for adapting the flow of air in each unit of the machine to the particular class of feathers that is to be treated, and I further provide means for varying the number of units in a machine.

It is another object of my invention to eliminate handling of the feathers and to provide an automatic machine.

Existing classing machines can be adapted to various mixtures of feathers and kinds of feathers only with difficulty or not at all. In particular, it was not possible to adapt each unit separately to a given kind of feathers, and the number of units was invariable.

According to my invention, the flow is regulated independently in each chamber or unit, and the number of units may be reduced or increased as desired so that a mixture of various classes of feathers is divided into a definite number of distinct classes or mixtures. This is particularly important because the mixtures of feathers as bought are altogether different according to their origin. For instance, Chinese feathers are of another character than Hungarian ones, and these again differ from Russian feathers.

In existing machines, a large amount of handling was performed, the several auxiliary steps, as charging and discharging the units, reversing of flaps, etc., were performed by hand, whereas in my machine all these operations are performed automatically and the machine requires no attendance after having been equipped with the proper number of units and regulated for the proper flow velocities in the units.

In the accompanying drawings, a machine according to my invention is illustrated by way of example:

Fig. 1 is a partly sectional elevation,

Fig. 2 is a plan view of the machine,

Fig. 3 is an elevation,

Fig. 4 is an axial section of a cam forming part of the control of the machine,

Fig. 5 is a section showing a modified feeding mechanism,

Figs. 6 and 7 are sections on the lines VI—VI and VII—VII in Fig. 5, respectively,

Fig. 8 is a section showing another modified feeding mechanism,

Fig. 9 is a detail.

Referring now to the drawings, and first to Figs. 1 to 4, *a*, *b*, *c*, *d*, and *e* are units of the machine, 1 is a supply hopper arranged above the units, 2 is a screen or partition surrounding a space 3, 4 is a passage opening from said space into the first unit *a*, 5 is a compressed-air pipe discharging feathers into the hopper 1, 6 is a stirring arm in the space 3 which is rotated continuously by a shaft 46 to which motion is imparted by means that will be described, its object being to clear the opening of the passage 4 and to prevent clogging thereof, 7 is another stirrer at the lower end of the passage 4 where it opens into the unit *a*, *E* is a table at the end of the passage 4 and 4' is an opening adapted to be closed by which the table is connected with the passage 4. A slide 4'' may be used for closing the opening 4'. The table *E* serves for inserting feathers by hand, if required.

As mentioned, any number of units *a*, *b*, etc., may be provided. 8 is a fan at the rear end of the machine, and 9 and 10 are suction pipes extending from the fan to the unit *e* and to a pipe 11 which extends above the units *b*, *c*, and *d*, and is connected with each by openings 27 and flaps 29. If desired, the pipe 11 might be connected with all of the units *b*, *c*, *d*, by opening all the flaps 29 at the same time, as illustrated.

12 are vertical adjustable partitions in the units *b*, *c*, and *d* by which the uptakes 13 in units may be extended or reduced, 14 are rollers at the lower ends of the partitions 12, 15 are rails on which the rollers are supported, 16, 16 are threaded spindles secured to the partitions near their upper and lower ends, 17 are threaded worm gears on the spindles, 18 are worms meshing with the gears 17, and 19 are hand wheels on the outside of the units on the shafts of the worms 100

by which the gears are turned and the spindles displaced, displacing, in turn, the partitions 12 in the direction of the arrows. Any other means might be provided for operating the partitions 12, and for insuring parallel displacement of the partitions.

34 is the usual spider or agitator at the bottom of each unit, and the determining factor for the classing of the feathers is the area of the passage just above the spiders. It may be desirable to arrange the walls of the passages at an angle in order to vary the velocity of the flow, for instance, to increase the velocity from the top to the bottom of the passage, if the velocity is too small at the top on account of the weight of the feathers. This might be effected by pivotally connecting the partitions 12 to their spindles (say by transverse pins 16' on the spindles fitting pivotally into brackets 12' of said partitions) and moving the spindles at the top and at the bottom through different distances.

20 are fixed partitions intermediate the units *b*, *c*, and *d*, 21 are holes in the partitions, 22 are slides for opening and closing the holes, 23 are racks on the slides, 24 are pinions meshing with the racks, and 25 are hand wheels for turning the pinions. 26 are openings at the top of each partition 20 connecting the uptakes 13 of the several units with the downward passages of the respective adjoining units, 27 are openings connecting said uptakes with the pipe 11, and 28, 29 are flaps for opening and closing the openings 26 and 27, respectively. Other devices than the flaps 28, 29 might be provided for controlling the said openings. 30 are screens preventing feathers from getting into the pipe 11. 31 and 32 are dampers for closing the pipes 10 and 9 respectively, and 33 is a flap for regulating the flow in the pipe 9.

35 are a set of collecting chambers at the rear end of the machine, one for each unit, 36 are pipes connecting the units *b*, *c*, *d*, and *e* with the chambers, and 37 is a pipe connecting the last chamber with the unit *a*, the pipe 37 being arranged on the opposite side of the machine for convenience. 38 are doors effecting air-tight closure of the chambers, 39 is a fan for generating a vacuum in the chambers, and 35' are sacks adapted to be secured to the ends of the pipes 36, 37 in each chamber 35 so that the several classes of feathers are each drawn into a separate sack.

The operation of the machine is as follows: The mixture of feathers from the hopper 1 gets first into the unit *a* through the passage 4. In this unit the flow generated by the fan 8 entrains all feathers except the so-called long feathers which are left in the unit *a*. The residual mixture is drawn into the unit *b* where the so-called heavy bed-feathers are separated, then into the unit *c* where the

lighter bed-feathers are left, then into the unit *d* in which the smallest feathers mixed with larger downs, so-called semi-downs, are separated, and in the unit *e* the very fine and best downs are separated. The machine as described is consequently adapted for the separation of five classes of feathers. If a mixture contains fewer, for instance, four classes, one of the slides 22 is opened to short-circuit two adjacent units. The short-circuited units make up a single unit and the same class or mixture of feathers is collected in them. For instance, if it is desired to separate only the long feathers and the heavy bed feathers but leave in the mixture the light bed feathers, the finest feathers, and all downs the units *c*, *d*, and *e* are short-circuited and I obtain in the unit *a* the long feathers, in the unit *b* the heavy bed feathers, and in the other units a mixture of light bed feathers, finest feathers, and downs.

If it is found that in a given mixture the several classes of feathers are not properly separated, or are not separated in the proper chambers, the flow of air is varied by displacing the partitions 12. By reducing the passages 13 the velocity of the flow in the unit concerned is increased and heavier feathers are entrained into the following unit. Another means for regulating the velocity is constituted by the flaps 29 through which a certain percentage of the air is by-passed into the pipe 11. The flow is normal as far as the by-passed unit, and reduced in that unit and in all following units.

The automatic means for regulating the machine will now be described. 40 is a horizontal shaft extending along the front end of the machine, 41 and 42 are cams on the shaft, 43 is a shaft extending above the shaft 40 which is rotated by a motor, not shown, 44 and 45 are worm gears through which the shaft 46 of the stirrer 6 is slowly rotated, the speed being about 1 to 3 revolutions per minute. 47 is a change-speed gear and 48 is a worm gear by which the shaft 46 rotates the cams 41, 42. The cams are rotated continuously during one classing operation which takes about 25 minutes. By their cam faces 55, 56 they control horizontal levers 49 which rock about a pin 50. The cam 41 controls only the stirrers 7. 51 is a pulley the shaft of which is connected with the worm gear 45, 52 is a fast-and-loose pulley on the shaft of the stirrer 7, 53 is a rod connected with the lever 49, and 54 is a bell-crank lever by which the belt is shifted when the lever 49 is rocked. As will appear from Fig. 3, the cam 41 is equipped with several short cam faces 55 and a longer cam face 56. The cam faces 55 serve for operating the stirrers 7, 7 periodically so that the machine has time for "digesting" the feathers, the long cam face 56 serves for the first charging of the machine, and the long depression between the

long cam face and the last short cam face 55 arrests the stirrers 7 while the units are connected with the sack chambers 35.

When emptying the units, the other cam 5 closes the flaps 31 and 32 so that the suction ceases, closes the dampers 28 and also a damper 57 which separates the first unit *a* from the other units. At the same time with the closing of the damper 57, or immediately 10 afterwards, the fan 39 is thrown in and the slides 58 of the suction pipes 36, 37 are opened. All connections between the fan 8 and the machine are now interrupted, all units are separated from the adjacent units and each 15 unit is only connected with one of the sack chambers 35 so that the feathers from each unit get into a definite sack chamber.

A system of links and levers 59 serves for operating the slides 58. A connection 60 is 20 made from this system to the flaps 31, 32. The dampers 28 and 57 are operated by a system 61.

Referring now to Figs. 5, 6, and 7, the stirrer 6 is replaced by a pair of helical conveyors 62, 62 which remove the feathers from the hopper 1. 63 are vertical passages conducting the feathers partly to the passage 4 and partly to a third helical conveyer 64 which conveys the feathers from the passage 30 63 at the right to the passage 4. Any number of conveyers may be provided instead of three.

Referring now to Fig. 8, 1 is a long hopper and the conveyers 62, 62 are combined into a 35 single unit 62', 63a is a passage about at the centre of the conveyer, and 63b is a passage at its end, the passage 63a delivering to the end of a conveyer 64' and the passage 63b being directly connected with the passage 4.

40 It is understood that other means may be provided for conveying feathers from the hopper 1 to the passage 4.

I claim:

1. A classifying machine comprising a 45 plurality of classifying units connected in tandem to form a continuous passage for a current of air and for the material to be classified, a suction device connected to the last of said units to produce such current, an auxiliary suction conduit leading to said device from points adjacent to the other units, and individual means controlling the connection of each of said other units with said auxiliary suction conduit.

55 2. A classifying machine comprising a plurality of classifying units connected in tandem to form a continuous passage for a current of air and for the material to be classified, a suction device connected to the last of said units to produce such current, an auxiliary suction conduit leading to said device from points adjacent to the other units, individual means controlling the connection of each of said other units with said auxiliary 60 suction conduit, and regulating devices ad-

justable within individual units and arranged to vary the cross sectional area of the passage within such units and thereby the velocity of the air current therein.

3. A classifying machine comprising a plurality of classifying units each formed with a passage through which the material is adapted to travel, one end of said passage in one unit being connected with the opposite end of the passage in the next unit, to establish within the units thus connected in tandem, a continuous path which includes the entire length of each of said passages, and movable means for establishing or cutting off at will, an additional connection between adjacent units at points between the ends of the passages of said units, thereby short-circuiting a portion of said passages.

4. A classifying machine comprising a plurality of classifying units each having an intake leg and an outlet leg, the outlet leg of one unit being connected with the inlet leg of the next unit to establish a tandem connection between the several units, and movable means for establishing or cutting off at will, an additional connection between adjacent units at such a point that material may pass directly from the intake leg of one unit to the intake leg of the next without passing through the outlet leg of the first-mentioned unit.

5. A classifying machine comprising a plurality of classifying units connected in tandem to form a continuous passage for a current of air and for the material to be classified, a suction device connected to the last of said units to produce such current, a separate sack chamber connected with each of said units, and a second suction device connected with said sack chambers to draw material into them from said units.

6. A classifying machine comprising a plurality of classifying units connected in tandem to form a continuous passage for a current of air and for the material to be classified, a suction device connected to the last of said units to produce such current, a separate sack chamber connected with each of said units, and suction connections associated with said sack chambers in such a manner as to draw material into said chambers from the respective units.

In testimony whereof, I have signed my name to this specification, this 3rd day of February, 1928.

HERMANN BAUER.
